UNITED STATES PATENT OFFICE.

JOSEPH SOSS, OF BROOKLYN, NEW YORK.

HINGE.

1,034,158.

Specification of Letters Patent.

Patented July 30, 1912.

Application filed April 15, 1912. Serial No. 690,707.

To all whom it may concern:

Be it known that I, JOSEPH Soss, a citizen of the United States, and residing at Brooklyn, in the county of Kings and State of New York, have invented certain new and useful Improvements in Hinges, of which the following is a specification, such as will enable those skilled in the art to which it appertains to make and use the same.

10 This invention relates to hinges for doors and other swinging devices, and particularly to what are known as invisible hinges of the class described and claimed in U. S. Letters Patent #1,009,108, granted to me Nov. 15, 1911, also #1,011,512 granted to me Dec. 12, 1911, also #1,019,096, granted to me March 5, 1912. These hinges and others of this class are used in connection with a stationary frame or support and a swinging 20 door or like member, and the said door or like member may be made according to the construction of the hinge, as shown in the patents referred to, to swing in either or both directions; and the object of this invention is to provide improved means for securing the hinge in or to the stationary frame or support whereby the swinging member or door may be quickly and easily detached from the frame or support, and as 25 quickly and easily replaced whenever necessary, a further object being to provide a hinge of the class specified which is particularly adapted for use in connection with the doors of automobiles or similar vehicles, 30 and the construction and operation of which is such that the swinging member or door may be easily detached with the operative parts of the hinge or hinges connected therewith whenever it is desired to wash or 35 clean the automobile, and whereby water will be prevented from entering or wetting the operative parts of the hinge, and also from entering the mortises or recess in the frame or support of the door and into which 40 parts of the hinge are inserted when mounting the door; a further object being to provide a hinge box or casing which is secured in the frame or support of the door and adapted to receive the corresponding hinge 45 butt or member with the operative parts connected therewith, and into which the corresponding hinge butt or member may be easily inserted in the mounting of the door, and whereby the door may be unmounted 50 or detached without injury to the frame or support, whenever necessary or desired; and

with these and other objects in view my invention consists in the construction, combination and arrangement of parts as hereinafter described and claimed.

The invention is fully disclosed in the following specification of which the accompanying drawing forms a part, in which the separate parts of my invention are designated by suitable reference characters in 60 each of the views, and in which:

Figure 1 is a face view of the hinge box or casing which I employ:—Fig. 2 is a side view thereof looking in the direction of the arrow 2 of Fig. 1:—Fig. 3 a face view of one 70 of the hinge butts adapted to be inserted into the box or casing, shown in Figs. 1 and 2: Fig. 4 a side view of the hinge butt, shown in Fig. 3 looking in the direction of the arrow 4 of said figure:—Fig. 5 a transverse 75 section of a part of a door frame and a part of a door provided with one form of hinge, the section through the hinge members being on the line 5—5 of Figs. 1 and 3 and showing the butt of Fig. 3 inserted in 80 the box or casing of Figs. 1 and 2, and showing the operative parts of the hinge and, indicating in dotted lines, the swing of the door, the hinge employed in this figure being such as to permit of the swinging of 85 the door in one direction only:—Fig. 6 a view similar to Fig. 5, but showing a modified hinge the construction of which is such as to permit the door to swing in both directions and showing the hinge box or casing of Figs. 1 and 2 used in both the door frame and the door. Fig. 7 a face view of 90 a hinge box or casing similar to that shown in Figs. 1 and 2, but showing a modification.

In Figs. 1 to 5 of the drawings, I have shown the improvement, which forms the basis of this application, applied to a hinge like that described and claimed in U. S. Letters Patent #1,009,108, hereinbefore referred to and in Fig. 6, I have shown the 100 said improvement applied to a hinge similar to that shown in Figs. 1, 2 and 3 of Patent #1,019,096, hereinbefore referred to.

In the drawing forming part of this specification, I have shown at *a* a part of a door frame and at *b* a part of a door, and in the practice of my invention, I provide, a hinge butt *c* adapted to be secured to or in the door *b* and a hinge butt *d* adapted to be secured to or in the door frame *a*, and I 105 also provide a hinge box or casing *e* which is adapted to be inserted into a corresponding

mortise in the door frame and to receive the hinge butt d , as hereinafter described.

The hinge butt c is the same as the corresponding hinge butt shown in Fig. 4 of Patent #1,019,096, and is provided with 5 rigid arms c^2 any desired number of which may be employed, links c^3 which are pivoted to the ends of said arms, and L-shaped links c^4 which are pivoted to said arms at c^5 , all 10 these parts being similar to corresponding parts shown in said patent.

The hinge butt d comprises a body portion d^2 having a central rectangular recess or chamber d^3 which opens through one side 15 thereof and through the face thereof, thus forming two face plates d^4 which project beyond the opposite side edges of the body portion, and said recess or chamber is provided with a back d^5 which does not extend entirely to the face of said butt, but terminates at d^6 and is provided with curved ribs d^7 parallel with the side edges of said body portion, and said side edges of said 20 body portion are rounded or made semi-circular in cross section, as indicated at d^8 and the face plates d^4 are provided with screw holes d^9 .

The hinge box or casing e which I employ comprises a face plate e^2 having a body portion e^3 provided centrally with a rectangular recess or chamber e^4 which opens through the face plate, and also through one side of the body portion and the opposite side of which is provided with a supplemental recess e^5 the back wall of which is curved inwardly and backwardly, as shown in Fig. 5, and the longitudinal or vertical dimensions of which are less than the longitudinal or vertical dimensions of the recess or chamber e^4 , and the top and bottom walls of the chamber or recess e^4 are curved or semi-circular, as shown at e^6 , to correspond with the form of the side edges d^8 of the body portion of the butt d , and the face of 35 the box or casing e is provided with recesses e^7 to receive the face plates d^4 of the butt d , and in the bottoms of which are screw holes e^8 to receive screws passed through the screw holes d^9 in said face plates.

50 The back or side of the body of the butt d opposite the side which is open is provided at the top and bottom thereof with ribs or projections d^{10} , and the open side of the box or casing e is provided with corresponding 55 grooves e^9 to receive said ribs or projections, and as thus constructed the butt d may be inserted into the box or casing e , which it will snugly fit, and said box or casing will be securely closed at all points, except the 60 chamber or recess thereof which opens through the face thereof, and into which the arms c^2 of the butt c pass and in which the link members c^3 and c^4 are movable, and in practice the links c^3 and c^4 are pivoted 65 between the ribs d^7 of the butt d by means

of pins f which are passed vertically there-through and through the back of said butt.

The arms c^2 of the butt c and the back wall of the chamber or recess e^5 are so formed that when the door is closed the 70 backs of said arms, or that portion thereof adjacent to the butt c , press against said wall, as clearly shown in Fig. 5, and the position of the links c^4 is such that there is a binding action between the separate parts 75 of the hinge and a lateral thrust which absolutely prevents the door from moving away from the frame in the plane thereof, but at the same time the said door will be free to swing, as indicated in dotted lines in 80 Fig. 5.

Although I have described the box or casing e as particularly adapted for use in, or in connection with the frame or support, the said box or casing may be used in connection 85 with the door, and in Fig. 6 I have shown a modification of the construction shown in Figs. 1 to 5 inclusive, in which said box or casing is used in connection with both the door frame and the door, and in which a 90 hinge construction is shown similar to that shown and described in Figs. 1 to 3 inclusive of Patent #1,019,096, hereinbefore referred to, with the exception that the hinge butts employed are the butts d . In other words 95 the hinge butts shown in Fig. 6 are similar to, or the same as, the butts shown in Figs. 3 and 4, and these butts are employed in connection with corresponding boxes or casings e . The movable parts of the hinge 100 shown in Fig. 6 however, are the same as the movable parts shown in Figs. 1 to 3 of Patent #1,019,096, and comprises S-shaped floating links g which extend into both the door and the frame, when the door is closed, 105 and to the ends of which are pivoted lock links h said links being pivoted to the butts d in both the door and the frame, as shown at h^2 , and L-shaped links i which are pivoted to the butts at i^2 and to the floating links g at i^3 , the construction and connection of 110 these link members being the same as in said patent, and with this construction the door may swing in both directions as shown and described in said patent.

115 With the construction shown in Figs. 1 to 5 inclusive, it will be understood, that the door butt of the hinge is permanently secured to the door, while the frame butt of the hinge is permanently secured, when in use, in the box or casing e , but may be detached therefrom whenever desired; while in the construction shown in Fig. 6 the door butt of the hinge and the frame butt of the hinge are both detachably secured in the boxes or casings e which are secured in the door and frame by means of screws passed through holes j in the face plates of said boxes or casings.

120 In Fig. 7 I have shown a modification of 130

the box or casing *e* in which the open side of the recess or chamber *e*⁴ is closed by a plate *e*¹⁰, and with this construction the back of said recess or chamber is also closed, and 5 the only opening thereinto is through the face plate, and when the corresponding butt is inserted the operative parts of the hinge are movable through said face plate with the exception of the lock links *c*⁸ in Fig. 5, 10 and *b* in Fig. 6.

It will be understood that this invention is not limited to the details of the construction of what are called the movable parts of the hinge herein shown and described, nor the 15 exact details of the construction of the box or casing *e*, and the butt or butts *d*, and various changes therein and modifications thereof, may be made, within the scope of the appended claims, without departing 20 from the spirit of my invention or sacrificing its advantages.

Having fully described my invention, what I claim as new and desire to secure by Letters Patent is:—

25 1. A hinge comprising two butt members connected by movable parts and one of which, when in use, is adapted to swing in a

horizontal plane, and a box or casing adapted to be secured in a support and into which one of said butts is adapted to be inserted 30 and to be detachably secured thereon.

2. A hinge comprising two butt members connected by parts, some of which are movable, and one of which, when in use, is adapted to swing in a horizontal plane, and 35 a box or casing adapted to be secured in a support, one of said butts being adapted to be inserted into said box or casing and to be detachably secured therein.

3. A hinge comprising two butt members 40 connected by movable parts, and boxes or casings adapted to be secured to a support and to a swinging device, said butt members being adapted to be inserted into said boxes or casings and to be detachably secured 45 therein.

In testimony that I claim the foregoing as my invention I have signed my name in presence of the subscribing witnesses this 12th day of April 1912.

JOSEPH SOSS.
